UNITED STATES PATENT OFFICE

163,168

HALF SLIP OR SIMILAR ARTICLE

Sadye Rosaria D'Amato, Jackson Heights, N. Y.

Application January 31, 1950, Serial No. 7,579

Term of patent 14 years

(Cl. D3—26)

To all whom it may concern:

Be it known that I, Sadye Rosaria D'Amato, a citizen of the United States and a resident of Jackson Heights, New York, N. Y., have invented a new, original, and ornamental Design for Half Slip or Similar Article, of which the following is a specification, reference being had to the accompanying drawing, forming a part hereof, in which

Figure 1 is a front elevational view of a half slip or similar article, showing my new design; and

I claim:

The ornamental design for a half slip or similar article, as shown.

SADYE ROSARIA D'AMATO.
